UNITED STATES PATENT OFFICE

2,622,336

GAUGE FOR INTERNAL TAPERED THREADS

Jean Raout, Paris, France

Application October 25, 1948, Serial No. 56,376
In France October 31, 1947

5 Claims. (Cl. 33—199)

1

The apparatus that forms the object of my invention is intended for one or more of the following purposes:

1. Measuring of the taper of tapered threads by measuring the distance of two diameters on the flanks;

2. Measuring of the pitch-diameter in a fixed plane;

3. Indirect measurement of the pitch.

It is especially suitable for measuring threads known as "A. P. I." threads (American Petroleum Institute).

It mainly consists of a combination of two threaded disks and micrometric barrels set coaxially in relation to each other and that are provided with adjusting marks and divisions that enable their comparative positions to be measured.

With the purpose of simplifying the understanding of the present description, the accompanying drawings illustrate in

Figure 1, an explanatory diagrammatic view;

Figure 2, a view partly elevational and partly cross-sectional of a first method of execution of the invention;

Figure 3, a similar view of a modification;

Figures 4 and 5 are cross-sectional views of design check gauges intended for setting the apparatus.

The apparatus is provided with a spindle 2 (Figure 2) on which is set, at the front part, a first feeler-disk 1 having a single turn of external tapered thread and an internal threaded part to be screwed onto corresponding threads on the spindle 2 to come into contact with the shoulder 15 on the spindle. The shoulder 15 is engraved with an adjusting mark 16, and a corresponding adjusting mark 17 has been drawn on the feeler-disk 1 and this mark 17 has to coincide with the mark 16 in order that the assembly of the feeler-disk is accurately done.

The spindle 2 is next fitted with a slider 8 that may either rotate or slide lengthwise on the said spindle, and may be fastened to it in any required position by tightening the screw 4.

The slider carries, screwed on it, and tightened against the shoulder 18, a second feeler-disk 3 having a single turn of external tapered thread. On the slider 8, also, a micrometric barrel 5 is assembled and is intended to bear on the end face of the test piece of which the tapered screw thread is to be measured. This barrel 5 may be screwed or unscrewed, by means of the micrometric screw thread 19, on the slider 8. Its position is measured by the displacement of the fiducial line 20 with regard to the graduated

2

edge of an adjustable thimble 6, fixed on the slider 8. The starting position of this graduated thimble 6 may be set by a previous adjusting operation, and fastened by tightening the screw 7.

The slider 8 carries, besides, at its rear portion another graduated thimble 9 that is capable of being secured in its starting position by means of a screw 21 and in front of which moves the fiducial line 22 of a micrometric barrel 10 that may be screwed or unscrewed in relation to the spindle 2 by means of a micrometric screw thread 23.

The spindle 2 is provided with an operating knob 12 secured thereto by means of a pin 11.

In order to measure the characteristics of a thread with this apparatus, the procedure is as follows:

(a) *Setting up.*—The first step is an adjusting operation by means of check gauges 24 and 25 (Figures 4 and 5), corresponding to the size of thread to be measured. Each gauge is provided with three sets of studs 26, the end surfaces of which constitute two reference planes including a standard length. These gauges are placed in the positions shown in dotted lines in Figure 2. The barrels 5 and 10 are then brought to contact and the graduated thimbles 6 and 9 are secured by means of their screws 7 and 21 so that their zeros coincide with the fiducial lines 20 and 22 of the barrels 5 and 10.

(b) *Measuring the taper.*—The pitch diameters A_1 and A_2 of the two threaded disk 1 and 3 being known, the calculation of the taper requires a measurement of the distance between them. This distance l_1 (Figure 1) is equal to l_2 plus a known constant value and may be measured consequently by means of the barrel 10 (Figure 2), the reading being made on the scale 9.

To carry out the measurement, first the threaded disks 1 and 3 are screwed in turn into the threaded part being examined. The barrel 10 is next brought to contact with the rear face of the slider 8. Then the reading, made on the scale of the graduated thimble 9, gives the departure from normal in the distance of the two disks, enabling any error in taper to be computed.

(c) *Measuring the pitch-diameter at gauge point.*—This datum is in relation to the distance l_2 (Figure 1) at which the rear feeler lies from the rear face of the test piece and this distance l_2 is equal to l_4 plus a known fixed value. A numerical table will enable the diameter sought for to be more easily evaluated when l_4 has been measured.

In order to make this measurement, the

threaded disk 3 is first screwed into the thread under test, then the barrel 5 is screwed until it comes to contact with the rear face of the threaded part. The distance l_4 is then read on the scale 6.

(d) *Indirect measurement of the pitch.*—After the instrument has been withdrawn from the threaded part, the two feelers are set up again in the position they were occupying when both were screwed in the threaded part, i. e. in the position recorded by the reading l_3 , previously made for taper measurement.

This leads up to the measurement of the pitch of a male taper thread, that may be easily carried out by means of any suitable auxiliary apparatus.

The modified apparatus illustrated in Figure 3 is so designed as to simplify for the reading of the taper the indirect measurement of the pitch. The two feeler-disks and the slider are set up as in the case of Figure 2, but rear thimble 27 is not graduated. It only carries a mark 28. The barrel 30, similar to 10 in Figure 2 is adapted to be brought to contact by micrometric motion, with the rear face of the slider 8. It carries also an indicia line 29 and on its rear portion, a fiducial line 33 working in conjunction with an adjustable graduated thimble 32, against which readings are made.

Under such conditions, the indirect measurement of the pitch takes place in the following way:

At the stage of the taper measurement carried out as stated above by reading the dimension l_3 , the mark 28 is brought opposite to the mark 29 and the thimble 27 is fixed on the slider in this position by means of the screw 34.

In order to set up again the comparative position of the feeler-disks, after withdrawing them from the threaded part, all that has to be done is to reproduce the reading l_3 and to bring again the adjusting marks 28 and 29 exactly opposite to each other.

The accuracy of the apparatus according to the invention is of a very high degree.

For a 25% taper, a variation of one division on the graduated thimble 32 (Figure 3) implies a variation of 2.5 microns in the taper.

For the barrel 5 in conjunction with the thimble 6, a variation of one division (corresponding to 10 microns) involves on the same taper—a variation of 2.5 microns on the value found for the diameter.

What I claim is:

1. An apparatus for measuring the characteristics of internal tapered threads comprising in combination a spindle, a first feeler mounted in adjusted position upon said spindle, a slider freely displaceable upon said spindle, a second feeler mounted in adjusted position upon said slider, a barrel having a front face, a rear reference face on said slider, said front face adapted

to abut said rear reference face on said slider, said barrel being adjustably mounted upon said spindle and a graduated thimble adjusted during initial setting and against which the position of said adjustable barrel is read, in order to measure the taper.

2. An apparatus as set forth in claim 1 in which said feelers are disks and wherein the rear face of the first feeler and the front face of the second feeler are so designed as to permit an initial setting by means of a gauge.

3. An apparatus as set forth in claim 2 in which said feelers are demountable and comprise a single turn of a conveniently shaped thread.

15 4. An apparatus for measuring the characteristics of a tapered thread comprising in combination a spindle, a first feeler mounted in adjusted position upon said spindle, a slider freely movable upon said spindle and having a rear reference face thereon, a second feeler mounted in adjusted position upon said slider, a micrometric barrel mounted upon said slider and having a flat front face designed to come to rest on the end face of a test piece upon said slider, a graduated adjustable thimble on said slider, the positions of said barrel being read against said graduated adjustable thimble, another micrometric barrel mounted adjustably upon said spindle and having a front face which can come to rest against the rear face of said slider, and a graduated thimble fixed during initial setting upon said spindle and against which are read the displacements of said adjustable barrel in order to measure the taper.

30 35 5. An apparatus for measuring the characteristics of internal tapered threads comprising in combination a spindle, a threaded primary feeler assembled in set position on said spindle, a slider that may be shifted likewise assembled on said spindle, a second threaded feeler assembled in set position on said slider, a micrometric barrel and a graduated thimble adjustably mounted on said slider cooperating with said second feeler, a second micrometric barrel movably mounted on said spindle, and micrometric measuring means 40 45 cooperating with said second barrel.

JEAN RAYOUT.
